FIG. 1 is a top plan view of a rake having a handle and pivotably engaged head showing our new design;
FIG. 2 is a top perspective view thereof, showing the head in an alternative, pivotably rotated position;
FIG. 3 is a bottom perspective view thereof;
FIG. 4 is an enlarged top perspective view of the head member thereof;

FIG. 5 is an enlarged bottom plan view of the handle thereof with a portion broken away, said broken away portion being a

continuation of the remaining portions, as further illustrated in FIGS. 1-3; and,

FIG. 6 is an enlarged fragmentary exploded side perspective

view thereof showing the manner of interaction of said handle

and head members.
